UNITED STATES PATENT OFFICE

JOHN A. ROBERTS, OF ROLFE, IOWA

ROOFING PAPER CUTTER

Application filed August 13, 1930. Serial No. 475,083.

This invention relates to a cutter for roofing paper or the like and generally aims to provide a construction wherein tar, rubber or other materials encountered by the knife during cutting will not adhere thereto so that the knife will always be free thereof and will not be hampered thereby in its operation.

Another object is to provide a novel construction having a handle provided with means therein to lubricate the cutter at the cutting edge as it operates in order to attain the end stated.

The more specific objects and advantages will become apparent from a consideration of the description following taken in connection with accompanying drawings illustrating an operative embodiment.

In said drawings:—

Figure 1 is a view showing the tool in side elevation, the operator's hand being suggested as operatively positioning the same as in use,

Figure 2 is an enlarged side elevation of the cutter alone,

Figure 3 is a central vertical sectional view of the cutter,

Figure 4 is a cross sectional view taken on the line 4—4 of Figure 2, and

Figure 5 is a cross sectional view taken on the line 5—5 of Figure 2.

Referring specifically to the drawings, the tool comprises a disk cutter as at 10 which is freely revolvable on a rivet or stud 10^a, which connects the cutter to a handle or operating body 11. Such handle consists of an upright grip portion 12. At the lower portion of the grip 12, an enlarged base 13 is provided which is bifurcated to accommodate the cutter 10 and which is extended beyond opposite sides of the disk to provide a rest as at 14 and 15, for the hand of the operator as suggested in Figure 1.

The grip 12 is hollow so as to constitute a reservoir and located therein is an applicator 16, of waste, cotton batting or the like which is saturated with kerosene, other oil or

the like. The upper end of the grip 12 is provided with a removable plug or cap 17, preferably screwed in place as at 18 as shown.

As appears in Figure 3, the interior of the grip 12 communicates with the bifurcation 50 of the base 13 and the applicator 16 constantly wipes or engages the periphery or cutting edge 19 of the cutter 10, constantly applying oil or other material thereto as the cutter is drawn over roofing paper or like material, 55 the oil-coated cutting edge preventing tar, rubber or other material of the roofing paper adhering to the cutter and interfering with effective cutting.

Various changes may be resorted to provided they fall within the spirit and scope of the invention.

I claim as my invention:—

1. A cutter device of the class described comprising a cutter member, a hollow handle carrying said cutter member, and applicator means in the handle to apply material to the cutting edge of the cutter to prevent adhesion thereto during cutting operation.

2. A tool of the class described comprising a hollow handle, a rotary cutter carried thereby, and an applicator carried within the handle and coacting with the cutter to apply material to the cutting edge of the cutter during a cutting operation to prevent adhesion of undesired matter to the cutter.

3. A tool of the class described comprising a hollow handle, a cutter carried thereby, an applicator carried within the handle and coacting with the cutter to apply material to the cutting edge of the cutter during a cutting operation to prevent adhesion of undesired matter to the cutter, and a base on the body adjacent the cutter for engagement by the hand of the operator.

4. A tool of the class described comprising a hollow handle, a rotary cutter carried thereby, an applicator carried within the handle and coacting with the cutter to apply material to the cutting edge of the cutter.

during a cutting operation to prevent adhesion of undesired matter to the cutter, a base on the body adjacent the cutter for engagement by the hand of the operator.

- 5 5. A tool of the class described comprising a hollow handle, a base therefor extending laterally therefrom and being bifurcated, a cutter pivoted in the bifurcation, applicator means within the handle to apply material to the cutting edge of the cutter and a closure for the upper end of the handle.

In testimony whereof I affix my signature.

JOHN A. ROBERTS.
